UNITED STATES PATENT OFFICE.

LOUIS MARCHAND, JR., OF PITTSBURG, PENNSYLVANIA.

DESIGN FOR A BASSINET-STAND.

SPECIFICATION forming part of Design No. 32,902, dated July 3, 1900.

Application filed May 12, 1900. Serial No. 16,520. Term of patent 7 years.

To all whom it may concern:

Be it known that I, LOUIS MARCHAND, Jr., a citizen of the United States, residing at Pittsburgh, in the county of Allegheny and State 5 of Pennsylvania, have invented and produced a new and original Design for a Bassinet-Stand, of which the following is a specification, reference being had to the accompanying drawing, forming a part thereof.

- The accompanying drawing is a perspective view of a bassinet-stand made in accordance with my present design.

The material or leading features of the present design are the laterally-projecting 5 arms A, terminating in downwardly-extending knobs or projections B and connected by

a longitudinally-extending horizontal bar C, together with the upwardly-extending end pieces D. The parts are circular in cross-section, and the points of union of the several members are slightly enlarged, still preserving, however, the circular shape in cross-section.

Having thus described my invention, what I claim as new is—

The design for a bassinet-stand as herein described and illustrated in the accompanying drawing.

LOUIS MARCHAND, JR.
